UNITED STATES PATENT OFFICE.

HARRY H. JENSEN, OF OAKLAND, CALIFORNIA.

ENVELOP.

1,046,467.

Specification of Letters Patent.

Patented Dec. 10, 1912.

Application filed February 23, 1912. Serial No. 679,322.

To all whom it may concern:

Be it known that I, HARRY H. JENSEN, citizen of the United States, residing at Oakland, in the county of Alameda and 5 State of California, have invented certain new and useful Improvements in Envelops, of which the following is a specification.

This invention relates to fire proof containers or envelops and has for its object 10 the construction of an envelop, or package which will preserve the contents from destruction by heat whereby the contents will still be preserved intact without serious injury thereto.

15 Another object of this invention is a production of a simple and efficient envelop structure which, although the outer surface may be entirely mutilated, the inner protector surface will still be preserved and the 20 marks of identification will still appear upon the protector surface.

With these and other objects in view this invention consists of certain novel constructions, combinations, and arrangements of 25 parts as will be hereinafter fully described and claimed.

In the drawings: Figure 1 is a front view of an envelop constructed in accordance with this invention. Fig. 2 is an inside view of 30 the blank from which the envelop is made before the same is folded. Fig. 3 is a view in section of the material used in constructing the envelop.

Referring to the accompanying drawings 35 it will be seen that the envelop comprises a body portion 1 having the usual end and side flaps 2. The envelop body is principally composed of a layer of paper 3, a layer of carbon 4 and a sheet, or layer of asbestos, or 40 other fire proof material 5. These layers of material are firmly cemented or otherwise secured together and the asbestos protector sheet 5 is placed upon the inside of the receptacle or envelop which is being 45 formed thereby presenting a finished outer face for constituting the neat appearance of the envelop, or other receptacle. Of course, it should be understood that it is not my 50 intention to limit myself to merely the construction of an envelop out of the material

as set forth, for the same material as described and hereinafter claimed may be used in constructing any desired package without departing from the spirit of the invention. Of course, it is unnecessary to use the 55 carbon sheet 4 other than on the face of the envelop where the name, or identification, to wit:—the address should occur.

When the sections of the envelop are assembled as above described the address of 60 the person receiving the letter, or marks of identification may be placed upon the face of the envelop, and through the medium of the transfer carbon 4 this address will be permanently transferred upon the protector 65 sheet 5 and should the sheets 3 and 4 become warm, or charred by burning, the envelop, or package will still retain its formation and the address, or marks of identification will be plainly visible upon the pro- 70 tector sheet 5.

Of course the fire proof layers may be insufficient to protect the contents from intense heat but even under such conditions the contents will be held intact and suffi- 75 ciently assembled to render it decipherable. It should be further observed that the asbestos protector sheet 5 owing to its stiffness will greatly protect the contents of the receptacle, which is made of the material as above set 80 forth.

What is claimed is:

1. A receptacle formed from sheet material comprising a fire proof layer, a finishing layer and a carbon sheet interposed be- 85 tween said layers for constituting a transfer means whereby marks of identification may be transferred upon the fire proof layer pro- 90 viding the outer layer and transfer layer should become destroyed.

2. A receptacle of the class described formed from sheet material comprising a layer of asbestos, a layer of finishing paper placed upon the outer face thereof and a carbon sheet interposed between said layers 95 for facilitating the transfer of marks of identification upon said asbestos sheet.

3. An envelop of the class described comprising a body, end flaps carried thereby, said body comprising a sheet of asbestos, 100

said end flaps comprising a sheet of asbestos, an outer sheet covering said body and end flaps, a transfer sheet carried by said body between said asbestos sheet and an outer sheet for transferring marks of identification from said outer sheet upon said protector sheet whereby the same may be identified providing the outer sheet should

become destroyed and removed from said protector sheet.

10

In testimony whereof I affix my signature in presence of two witnesses.

HARRY H. JENSEN.
